H. LOEB.
ELECTROLYZING VAT.
APPLICATION FILED JAN. 10, 1919.

Patented Mar. 22, 1921.

UNITED STATES PATENT OFFICE.

HENRY LOEB, OF MEMPHIS, TENNESSEE.

ELECTROLYZING-VAT.

1,372,176.

Specification of Letters Patent. Patented Mar. 22, 1921.

Application filed January 10, 1919. Serial No. 270,541.

To all whom it may concern:

Be it known that I, HENRY LOEB, a citizen of the United States, residing at Memphis, Shelby county, and State of Tennessee, have invented and discovered certain new and useful Improvements in Electrolyzing-Vats, of which the following is a specification.

In the manufacture of chlorin by the process of electrolysis a vat is employed formed of material such as glazed pottery, earthenware, or vitreous substance, capable of resisting the passage of electric current. In the use of such vats of common construction great care must be exercised to avoid breakage or cracking because of the uneven temperature between the outside and the inside, or because of too high temperature. Such vats are comparatively expensive and their frequent cracking or breakage constitutes a material item in the overhead expenses of running establishments employing such apparatus in the conduct of their business, such as laundries, cotton mills, etc., where large quantities of chlorin are made and used for bleaching purposes. It is a common experience to have such vats break almost as soon as installed, or last only a very few days, and when once broken or cracked it has been the custom to discard them as worthless, substituting a new one at a cost of approximately \$125 for a medium sized vat. The expense of the vat is also added to by the waste of the chlorin and the electric current resulting from its escape through the crack as soon as the breakage occurs, and frequently amounting to considerable before it is discovered and the waste arrested.

The object of my said invention is to provide a means for not only insuring against the destruction of the vat by breakage and its consequent loss, but also against the waste of the chlorin and the electric current should any break in the porcelain portion of the vat occur, all as will be hereinafter more fully described and claimed.

The accompanying drawing which is made a part hereof and on which similar reference characters indicate similar parts is a perspective view of a vat constructed and arranged in accordance with my said invention, one corner of the same being broken away to show the construction more clearly.

In said drawing the portion marked A represents the porcelain vat, and B and C the positive and negative electrodes, respec-

tively, all of which are of the construction and type commonly employed in the practice of the process of making chlorin which is well understood and needs no elaborate description.

The porcelain vat A is inclosed in a wooden case 10, made of heavy boards and securely bound together by straps 16, which may be connected at their corners by engaging bolts 65 and nuts 17, or in any other appropriate manner. Said case 10 is larger than the vat A so that when said vat is centered therein there will be a space of a few inches on all sides between the vat and the case, 70 including the bottom thereof. This space is filled with an insulating bituminous composition or material preferably asphalt, which I have found to be very serviceable for the purpose. This material covers the 75 outside surface of the vat A on all sides and bottom, thus forming a structure in which the porcelain part of the vat is securely packed in a material that is capable of resisting and retaining the heat and also resisting the passage of the electric current, thus insulating the vat from any waste of the current and surrounding it with material of a character and consistency that will promptly close any crack that may occur, 80 should one occur during operation.

A discharge spout 13 and terminal connectors 14 and 15 are indicated, all of usual form and requiring no special description.

In the drawing I have illustrated the vat 90 A as having a crack 12 in the corner thereof, the same being exposed by the breaking away of the other portions of the structure. This is merely for purposes of illustration and I desire it understood that the invention 95 is for use with unbroken vats as well as for use with those that have been cracked or broken. In actual practice I have taken vats that have been broken and discarded, and by fitting the parts together and packing them in a wooden case, as 10, in the thick asphalt packing material 11, completely restored such vats to a condition where they have proven just as serviceable in use as when they were new, thus recovering from 105 the scrap heap, at small expense, these valuable vessels and putting them to their original use, thereby saving a considerable item in the overhead expenses of the plant. The invention, therefore, has a twofold purpose: 110 that of protecting perfect porcelain vats against breakage and that of restoring

broken vats to a condition of perfect utility; as well as the further purpose of economy in operation by saving heat and electric current.

5 In practice I have found that the porcelain vats, as heretofore used, will crack under a temperature of from 115° to 125° F. A vat constructed and protected in accordance with my said invention can be 10 safely heated to beyond any temperature needed. Asphalt will liquefy at about 300° F. and water vaporize at about 212° in an open vessel. These vats have been tested to a temperature that will boil water, without 15 cracking them, while the vats as formerly used could not withstand a temperature nearly approaching the boiling point of water.

While I have used wood and asphalt for 20 the case and packing, respectively, I desire it understood that in using these terms herein, I intend to include in their meaning any other materials found suitable for these parts.

25 Having thus fully described my said in-

vention, what I claim as new and desire to secure by Letters Patent is:

1. A vat for use in making chlorin by electrolysis comprising a vessel of glazed pottery, a casing of wood surrounding said vessel, and a packing of asphalt between said vessel and said casing, substantially as set forth.

2. A vat for making chlorin by electrolysis comprising a vessel of glazed pottery, a 30 reinforced casing of wood, means for binding said casing together, a packing of asphalt interposed between said vessel and said casing, and a discharge spout running from the interior of said vessel through said 35 packing and casing to the outside, substantially as set forth.

In witness whereof, I have hereunto set my hand and seal at Memphis, Tennessee, this 3rd day of January, A. D. nineteen 40 hundred and nineteen.

HENRY LOEB. [L. S.]

Witnesses:

ALBERT KIME,
JOHN W. FARLEY.
